ROBERT F. MEGGITT, OF CHEBOYGAN, MICHIGAN

FLY SWATTER

Application filed June 25, 1928. Serial No. 287,970.

It is well known that the flexible paddle of a fly swatter often wears out before the handle, and this invention aims to provide novel means whereby a new paddle can be put on an old handle of a fly swatter.

Figure 1 shows in elevation, a device constructed in accordance with the invention, parts being broken away;

Figure 2 is an elevation wherein the frame 10 of the fly swatter is viewed edgewise, parts being broken away;

Figure 3 is a composite perspective view showing parts of the frame separated, portions being broken away.

15 The frame of the fly swatter is made out of wire or similar material having some resiliency. The frame includes a handle, which, as a whole, is marked by the numeral 1. The handle 1 includes a head made up 20 of a cross piece 2 and converging arms 3 connected to the ends of the cross piece 2. The parts 4 of the arms 3 which are immediately adjacent to the cross piece 2 converge less pronouncedly than do the parts 5 of the 25 arms.

The parts 5 of the arms 3 are twisted together as at 6 and extended in parallel relation, as at 7, to form the stem 8 of the handle, the stem 8 terminating in an eye 9 30 whereby the swatter may be conveniently suspended. To facilitate the grip of the head member of the handle on the paddle 10 of the fly swatter, the parts 4 of the arms 3 are reversely curved, as at 11, near to the 35 ends of the cross piece 2.

The frame of the fly swatter includes a jaw, designated generally by the numeral 12. The jaw 12 comprises a cross piece 14 and arms 15, the parts 16 of the arms 15 which are immediately adjacent to the cross piece 14 converging less pronouncedly than do the parts 17 of the arms 15 which are remote from the cross piece 15. The parts 17 terminate in attaching elements, preferably oppositely facing hooks 18.

The paddle 10, hereinbefore referred to, preferably is flexible, and includes a rim or binder 19 and a body 20 within the binder, the body being made of wire netting in the 50 present embodiment of the invention, al-

though another material might be employed if desired. In the edges of the paddle 10, near to the inner end of the paddle, recesses 21 may be formed.

In practical operation, the paddle 10 is extended across the piece 2 of the handle and between the arms 3 of the handle, the parts 4 of the arms 3 being received in the recesses 21 that are formed in the edges of the paddle 10. The paddle 10 extends down far enough along the arms 3 so that the parts 5 of the arms 3 cut across the corners of the paddle 10, as shown at 22 in Figure 1. The jaw 12 now is mounted in place, the paddle 10 being engaged between the cross piece 2 of the handle 1 and the cross piece 14 of the jaw, as shown in Figure 1. The parts 16 of the arms 15 of the jaw 12 are crossed as at 23 upon the parts 4 of the arms 3 of the handle 1, and the inner corners of the paddle 10 are bound between the members 5 of the handle 1 and the members 17 of the jaw 12. The parts 17 of the jaw are crossed on each other, as shown at 24, and the attaching elements or hooks 18 are engaged in opposite directions around the twisted part 6 of the stem 8. Owing to the fact that the arms 3 of the handle 1 are reversely curved as shown at 11 in Figure 2, the cross piece 14 of the jaw 12 tends to slide in the direction of the arrow A in Figure 2 of the drawings, and the paddle 10 is bound the more securely between the cross piece 2 of the handle and the cross piece 14 of the jaw 12.

Having thus described the invention, what is claimed is:—

In a fly-swatter, a frame comprising a stem, arms projecting from the stem, and a cross piece connecting the arms, the arms embodying curved portions disposed at the ends of the cross piece; a jaw comprising a cross piece and arms, the cross piece of the jaw extending across the arms of the frame in approximate parallelism to the cross piece of the frame; the cross piece of the jaw being slidably engaged with the curved portions of the arms of the frame to cause the cross piece of the jaw to slide toward the cross piece of the frame, thereby to form a paddle-grip; the jaw being freely remov-

able from the frame and being movable longitudinally of the frame to permit the cross pieces to function as aforesaid, and means for effecting a slidable and releasable connection between the arms of the jaw and the stem.

5 In testimony that I claim the foregoing as my own, I have hereto affixed my signature.

ROBERT F. MEGGITT.
